ABDOMINAL SUPPORT

Josephine L. Holt, Oakland, Calif.

Application December 7, 1945, Serial No. 633,547

2 Claims. (Cl. 2-27)

1

This invention relates to abdominal supports, particularly for women.

Many initially excessively fat women succeed, by dieting or otherwise, in reducing their weight, and the size of the abdominal region, considerably. However, the previously distended abdominal muscles do not shrink and as a result, an apron-like fold of muscular tissue remains which must be confined for both appearance and comfort.

The main object of the present invention is to take care of this condition by the provision of an abdominal support shaped so as to form a pocket for the aforementioned excess overhanging tissue, and thus contain and hold the same in a proper and comfortable position.

Another object is to provide a support of this character which may be made as an attachment adapted to be mounted on a conventional corset.

In the drawings:

Fig. 1 is a front elevation of the abdominal support.

Fig. 2 is a rear view of the same.

Fig. 3 is a transverse section on line 3-3 of Fig. 1.

Fig. 4 is a perspective view of the support as mounted on a corset.

Referring to the characters of reference on the drawings, the support comprises a knit panel 1 of suitable size having tapes 2 down its opposite side edges; a row of eyelets 3 being secured on and projecting from the outer edges of the tapes.

The panel 1 is reinforced and made to assume a convex form in a vertical plane by means of spaced vertical stays 4 retained in casings 5 on the front of the support; the central casing 5a being wider than the remainder as shown in Fig. 1.

The panel 1 is cut convex on its lower edge and at said edge is provided with a casing 6 which follows the convex curvature and thru which a draw tape 7 extends; the ends of this tape being adjustably engaged with buckles 8 on the lower end of side tapes 2. On the opposite or back side of the panel 1 is a relatively short flexible knitted panel 9, which is attached at its sides to the adjacent eyelets 3 by lacings 10.

Along its lower edge, panel 9 is secured to the panel 1 adjacent its lower edge by a plurality of bow tapes 11 and a pocket 12 is formed between the panels as shown in Fig. 3.

2

A horizontal tuck 13, which may vary in size so as to adjust and alter the contour of panel 9 as may be desired, is taken in said panel in the central plane thereof.

5 A loose elastic band 14 extends along the upper edge of panel 9 being threaded thru a row of tape loops or lacings 15 attached to panel 9; the band 14 at its lower ends being attached to certain ones of the eyelets 3 depending on the 10 height desired.

In use, the support is attached to a conventional corset 16 by lacings or other connections 17 between the corset and eyelets 3 as shown in Fig 4. When thus mounted on a corset, the support is in position to receive the overhanging and loose tissue "apron" of the abdomen of the wearer.

I claim:

1. An abdominal support comprising a flexible 20 panel adapted at its side edges for connection with the back side of a corset; reinforcing stays secured on the panel and another relatively short panel connected along its sides and lower edge to the sides and lower edge of the first named panel; 25 an elastic band connected at its ends to the first named panel at adjustable points in the height thereof, and loops along the top of the first named panel through which the band is threaded.

2. An abdominal support comprising a flexible 30 panel adapted at its side edges for connection with the back side of a corset and vertical stays secured on the outer face of the panel and arranged so that said panel is held to a convex form in a vertical plane; a tubular casing along 35 the lower edge of the panel, a tape threaded through the casing, and members on the panel at its side edges and in line with said tape for adjustable connection therewith.

JOSEPHINE L. HOLT.
